CLAIM

The ornamental design for a tire for vehicles, as shown and described.

DESCRIPTION

FIG. 1 is a perspective view of a tire for vehicles showing our new design it being understood that the tread pattern is repeated uniformly throughout the circumference of the tire and the opposite side is the same as that shown;

FIG. 2 is a front elevational view thereof; and

FIG. 3 is a side elevational view thereof.

FIG. 1

FIG. 2

FIG. 3
